CLAIM

The ornamental design for a lamp, as shown and described.

DESCRIPTION

FIG. 1 is a top, and front perspective view of a lamp showing my new design;

FIG. 2 is a bottom, and rear perspective view thereof;

FIG. 3 is another bottom and rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 in FIG. 1; and,

FIG. 11 is an enlarged view of portion 11 in FIG. 2.

The long dash-short dash broken lines define the boundaries of enlarged views and form no part of the claimed design.

1 Claim, 11 Drawing Sheets
